J. BENZION.
SAFETY DEVICE FOR CHARGED SODA WATER TANKS.
APPLICATION FILED OCT. 9, 1917.

1,287,838.

Patented Dec. 17, 1918.

Inventor
Joseph Benzion,
By his Attorney,

Willis Fowler.

UNITED STATES PATENT OFFICE.

JOSEPH BENZION, OF NEW YORK, N. Y.

SAFETY DEVICE FOR CHARGED SODA-WATER TANKS.

1,287,838.

Specification of Letters Patent.

Patented Dec. 17, 1918.

Application filed October 9, 1917. Serial No. 195,634.

To all whom it may concern:

Be it known that I, JOSEPH BENZION, a citizen of the United States, residing in New York city, in the county of New York and State of New York, have invented certain new and useful Improvements in Safety Devices for Charged Soda-Water Tanks, of which the following is a specification.

In the use of soda and aerated water apparatus, the vessel or tank containing the water charged with carbonic acid gas under high pressure frequently has its contents subjected to a greatly increased pressure which often causes the metal tank to burst and this results in damage to the surroundings and sometimes causes the death of persons nearby. My present invention seeks to overcome this drawback by providing the ordinary valved cock of the tank with a relief valve which is automatically opened whenever the contents of the tank has its pressure increased above a certain predetermined degree and thereby reduces the pressure to the desired and safe degree, whereupon the valve automatically closes and preserves the desired pressure in the tank.

I have illustrated the invention in the accompanying drawings, wherein:—

Fig. 1, is a side view of the improved valve fitting shown as mounted in operative position on a soda-water tank, the upper portion only of which is shown and that is in vertical central section.

Fig. 2, is a vertical sectional view of the parts shown in Fig. 1, the plane of the section being indicated by the line 2—2, in Fig. 1.

Fig. 3, is a vertical sectional view of the valve-fitting shown as detached from the tank, the plane of the section being indicated by the line 3—3, in Fig. 2.

Fig. 4, is a vertical sectional view taken through the relief valve, and shows the same in open position.

Referring to the drawings in which like numbers of reference designate like parts throughout, 1 is a closed metal vessel or tank having at its upper end an outlet 2, threaded upon its interior for the reception of a threaded tubular neck 3, of the valve-fitting 4, which is thereby detachably mounted on the tank. A pipe 5, is secured in the mouth of the neck and extends to a point near the bottom of the tank for drawing off the contents thereof in the usual way. A

metal washer 6, is interposed between the valve casing 4 and the outlet extension 2, and surrounds the neck so as to make a gas and water tight joint.

A passage 7, leads through the neck 3, to the valve-seat 8, in the valve-chamber 9, in the casing and this passage is controlled by the hand-operated valve 10, having a stem 11, externally screw-threaded at 12, and which thread takes into a corresponding thread in the interior of the boss 13, formed on the valve-casing and through which the stem passes. The outer end of the valve stem is provided with a hand-wheel 14, for manipulating the valve to control the flow of liquid from the tank through the outlet passage 15, leading from the valve-chamber 9, through the tubular extension 16, which is provided with an external thread 17, for receiving a suitable pipe connection through which the liquid may be drawn off and which is not shown.

One side of the casing 4, is provided with a suitable projecting part 18, formed with a valve-chamber 19, in which is located the valve-seat 20, surrounding the mouth of the by-passage 21, which extends through the wall of the neck 3, and leads into the interior of the tank so as to be in free communication therewith. The by pass communicates with the outer air by way of the valve-chamber 19, and a vent 22, extending through the wall of the same. A valve 23, having a soft washer 24, closes on the seat 20, and controls the by-pass and its communication with the vent 22, and this valve has a stem 25, around which is placed a coiled spring 26, the inner end of which bears against the valve while the outer end thereof bears against an adjustable cup-shaped plug 27, having a thread 28, which works in a corresponding thread 29, in the outer part of the chamber 19. The screw-plug 27, has on its outer face a slot 30, adapted to receive the blade of a tool by which the plug 100 may be turned either way on its axis to adjust it so as to vary the spring action on the valve. When the plug is screwed inwardly it increases the pressure of the spring on the valve and when turned in the opposite direction it weakens the pressure of the spring. Whenever the relief-valve 23, is lifted from its seat by the pressure of the contents of the tank which are at all times in free communication with said valve, the 110

contents of the tank which are at all times in free communication with said valve, the 110

interior of the tank is vented around the valve and through the vent 22, to the outer air.

From the foregoing description, it will 5 be readily understood that in filling the tank at the factory with water charged with carbonic acid, or other gas, under a high pressure, a pressure gage is used so that a predetermined degree of pressure may be 10 placed upon the contents of the tank and then the relief-valve is adjusted to open automatically at a slightly greater pressure and the tank is then shipped to a customer for use in connection with a fountain. If 15 in such use or while being transported or during storage the pressure of the contents of the tank should become unduly increased, the relief-valve will automatically open and reduce such pressure to the safety point and 20 thereby prevent a possible explosion of the tank.

It will be noted that all of the parts except the movable and detachable ones, are made in a single metal casting, and that the 25 relief-valve is conveniently made a part of the main valve fitting so that a separate part is not employed for such safety device. The chamber 19, of the relief valve is formed in a solid part of the fitting and the by-pass 30 21, may be cast or may be bored through the walls of the fitting as indicated in the drawings. The means for regulating the tension on the relief-valve are well housed and protected from damage by rough handling of the tank when in use.

My improvements may be applied to valve-fittings of the ordinary kind which are now used in conjunction with soda-water tanks and I wish to be understood as 40 not limiting my invention to the particular constructions herewith shown, for modifications may be made in the different parts thereof without however departing from the spirit of the invention.

Having thus described my invention, what 45 I claim and desire to secure by Letters Patent is:—

1. The combination with a charged-water tank, of a valve-fitting having a centrally 50 chambered casing and provided with a downwardly extending neck and a lateral

neck each provided with a passage extending through the neck and leading to the central valve-chamber and one of said necks being adapted for engagement with a pipe-connection and the other being adapted to connect with the interior of the tank, a main valve in said central chamber controlling said passage in the depending neck, a valve-stem connected with the main-valve 60 and extending through and provided with a bearing in said boss, a lateral projection on said casing between said boss and lateral neck and provided with a safety-valve chamber, a by-passage leading from said safety-valve chamber through said depending neck to the end thereof so as to communicate with the interior of the tank, a valve-seat in the safety-valve chamber surrounding said by-passage, an adjustable spring-actuated valve 65 coöperating with said seat, and a vent connecting said safety-valve chamber with the outer air, substantially as described.

2. The combination with a charged-water tank, of a valve-fitting having a casing 75 formed with a main-valve chamber and provided upon its exterior with two necks each having a passage extending through it and leading to the main-valve chamber, one of said necks being adapted for attachment to 80 a pipe-connection and the other being adapted to connect with the interior of the tank and a drawing-off pipe secured to said latter neck and disposed within the tank for drawing off the liquid contents thereof, a 85 main-valve in said chamber for controlling the passage in the neck having the drawing-off pipe attached thereto, a by-passage leading from the exterior of the casing to a point on the inner end of the neck connected 90 with the tank so as to communicate with the interior of the tank at its upper end, and an adjustable spring-actuated safety-valve controlling said by-passage, substantially as described.

In testimony whereof, I have hereunto set my hand in the presence of the two subscribing witnesses.

JOSEPH BENZION.
